(57) **CLAIM**

We claim the ornamental design for a portion of a control head for use with dental equipment, as shown and described.

DESCRIPTION

FIG. 1 is a right side perspective view of a portion of a control head for use with dental equipment showing our new design;

FIG. 2 is a top plan view thereof;

FIG. 3 is a front elevation thereof;

FIG. 4 is a rear elevation thereof; and,

FIG. 5 is a right side elevation thereof, the side opposite being a mirror image.

The broken lines shown herein are for illustrative purposes only and form no part of the claimed design.
